PACKER BACK-UP RING STRUCTURE
Glenn L. Loomis, Pasadena, Tex.; Jean Doyle Loomis,
executrix of Glenn L. Loomis, deceased, assignor to
Jean Doyle Loomis

Filed Feb. 2, 1962, Ser. No. 170,537
3 Claims. (Cl. 166—201)

The present invention relates to a packing structure for use in forming a seal between a rod-like element and a surrounding wall of a well pipe and, more particularly, to a packing structure incorporating an improved packer back-up ring for preventing cold and flow of a packer when the packer is set against the wall of a well pipe and then subjected to high pressures.

The packing structure of the present invention is preferably intended for use in a device for testing well pipe or the like for leaks, but it may also be used with other well equipment when it is desired to set a packer in the well pipe and the packer is subsequently subjected to extreme pressures. A typical testing device for which the packing structure of the present invention is preferably used is disclosed in my copending United States application serially numbered 170,711 and entitled "Testing Tool for Well Pipe or the Like" and filed concurrently herewith. The subject matter of the testing tool disclosed in the aforementioned copending application is incorporated by reference herein for that purpose.

In recent years, the flow tubing for oil or gas wells or the like has been made with an internal plastic lining. The plastic lining which is usually coated on the interior of the pipe provides protection to the metal pipe from the corrosive action caused by acids and other fluids flowed therethrough. The plastic lining of the sections of pipe is quite fragile and may be easily damaged if contacted by a well tool having a harder surface than the lining. In my aforementioned copending application, there is disclosed completely a well tool suitably coated on its exterior surfaces with a material as soft as or softer than the lining so as to protect the lining as the well tool is inserted into the pipe.

The back-up rings heretofore used in association with resilient packers to prevent cold flow of the packer under extreme pressure conditions have been made from arcuate metallic segments which were simultaneously expanded into engagement with the wall of the pipe when the packer was expanded. Such a back-up ring is disclosed in my copending application Serial Number 754,197, filed August 11, 1958, and entitled "Tester Apparatus for Oil Wells or the Like" and now United States Patent No. 3,038,542 issued June 12, 1962. It has been found that the engagement of the metallic segments of the expandable segmental back-up ring with the plastic lining when the same are expanded by the annular pressure exerted by the packer immediately crushes the lining in the pipe and thus, when the well tool is removed, the effectiveness of the lining has been materially reduced as the pipe can be subjected to corrosive action at this point.

An important object of the present invention is to provide a packer back-up ring structure utilizing an expandable segmental ring made of arcuate metallic segments, the expansion of the ring being controlled to prevent the walls of the segments from engaging and crushing the lining in a plastic lined pipe.

Another object of the present invention is to provide a packing structure having an expandable segmental packer back-up ring associated therewith in which the segments of the ring are generally expanded radially outwardly a predetermined distance whereby the metallic segments do not engage the lining of a plastic lined pipe but still provide an effective block to the cold flow of the packer.

Still another object of the present invention is to provide an expandable segmental packer back-up ring structure comprising metallic arcuate segments, the back-up ring structure including means to positively limit the amount of radial movement of the segments of the ring.

5 Since it is desirable to provide well tools with greater clearance from the walls of a plastic lined pipe so that the tools can be inserted into the pipe with less danger of contacting the lining, the annular clearance necessary for expanding the back-up ring in order to prevent flow of the packer is increased. In view of this, it is a further object of the present invention to provide an expandable segmental back-up ring capable of being expanded over an annular distance greater than heretofore realized and then returned to its original retracted position.

10 15 These and other objects of the present invention will appear more fully in the following specification, claims and drawings in which:

FIGURE 1 is an exploded perspective view of a packer 20 back-up ring structure of the present invention, one of the segments of the segmental ring being omitted for the purpose of clarity and the retainer band being shown partly in section;

FIGURE 2 is a vertical section on a reduced scale and 25 partly in elevation, the view illustrating the packing structure of the present invention as applied to a testing device;

FIGURE 3 is an enlarged fragmentary sectional view 30 through a portion of one segment of the expandable segmental back-up ring of the present invention and illustrating the same in a retracted position;

FIGURE 4 is a view similar to FIGURE 3 but illustrating the position of the segment after the back-up ring has been expanded; and

35 FIGURE 5 is an exploded perspective view similar to FIGURE 1 but illustrating a modified form of expandable back-up ring structure of the present invention.

Referring now to the drawings wherein like character and reference numerals represent like or similar parts, 40 the packer back-up ring structure of the present invention is best shown in FIGURE 2 utilized on the lower end of a testing device generally designated by the numeral 10. The testing device 10 is of the type disclosed in my aforementioned applications and generally includes an elongated tester body having spaced packers mounted thereon 45 and adapted to be expanded into engagement with the walls of a well pipe 12 or the like. Suitable fluid passages are provided in the testing device 10 for supplying hydraulic fluid under pressure to pistons acting against the 50 packers, the pistons compressing the packers longitudinally and thus expanding them transversely so that they form sealing engagement with the well pipe 12 to define a sealed off section of well pipe to be tested.

The testing tool 10 is also provided with suitable pressure responsive valves which permit the application of the hydraulic fluid under pressure to the sealed off space between the packers in order to accomplish the test of the well pipe. A joint or connection between two sections of well pipe or the well pipe wall itself may be 55 tested by such a pressure method. After the well pipe has been tested, the pressure on the hydraulic fluid in the testing tool 10 is relieved and the packers are relaxed so that the testing tool may be moved to a different position in the well pipe to provide for a subsequent test.

60 65 The testing procedure briefly described above is disclosed in detail in my aforementioned pending application entitled "Testing Tool for Well Pipe or the Like" as well as in my prior United States Patent No. 2,731,827, issued January 24, 1956.

70 Referring now in detail to FIGURES 1 through 4, inclusive, the well pipe 12 is of the type having a protective lining C made of a plastic material such as an epoxy

resin or the like. The packing structure of the present invention generally designated by the numeral 14 is carried on the elongated body of the testing device 10 which may be considered for the purposes of this description as a rod-like element 16. Packing structure 14 includes a substantially cylindrical resilient packer 18 made of an elastomeric material such as rubber, synthetic rubber or the like, a piston element 20 and a back-up ring structure 22. The piston 20 abuts one end of the packer and may be moved longitudinally toward the packer by application of hydraulic fluid under pressure to the interior of the same. The rod-like element 16 is provided with an abutment portion or nose end 24 and the back-up ring structure 22 is interposed between the abutment portion 24 and the end of the packer 18 opposite the end abutting piston 20. It will now be understood that when the piston 20 is extended or moved downwardly as viewed in FIGURE 2 toward the packer 18, it will cause the packer to compress longitudinally against the back-up ring structure 22 and expand transversely into sealing engagement with the wall of the flow tubing or well pipe 12.

Since the resilient packer 18 is made of an elastomeric material, it will not damage the plastic lining C of the pipe when it engages the same. As shown in FIGURE 2, the exposed portions of the testing device 10 including the piston 20 and the rod-like element 16 with its abutment portion 24 are coated with a non-metallic material M softer than the plastic lining C of the pipe. This feature of the well tool is disclosed in detail in my aforementioned application entitled "Testing Tool for Well Pipe or the Like."

The back-up ring structure 22 includes an expandable segmental back-up ring 26 positioned intermediate a pair of annular ring elements 28 and 30. The expandable segmental ring 26 is comprised of a plurality of arcuate metallic segments 32 having a curved outer peripheral surface 34. Each segment 32 is provided with a groove 36 in its outer peripheral surface, the grooves 36 of the segments defining a continuous groove when the segments are positioned together as a ring. The grooves 36 of the segments are adapted to receive an endless retainer band 38 made of a resilient elastomeric material such as rubber, synthetic rubber or the like. The retainer band 38 maintains the segments 32 of the ring unit 26 in a retracted position but also permits the segments to be expanded substantially radially outwardly of the longitudinal axis of the rod-like element 16. While the metallic segments 32 disclosed herein are simple arcuate segments which abut each other on their radial faces, the segments could be made to overlap one another in the manner taught in my United States Patent No. 3,038,542 without departing from the spirit of the present invention.

In order to cause the segmental back-up ring 26 to uniformly expand and retract in a radial direction, the ends of each of the segments 32 are provided with inwardly double-tapered surfaces 40 and 42 separated by an outwardly facing step surface or abutment 44 therebetween. When the segments 32 are assembled as a unit and maintained in retracted position by the retaining band 38, the double tapered surfaces 40 and 42 of the segments define inverted double cone ends. Each of the annular rings 28 and 30 are provided with double cone surfaces 46 and 48 separated by an inwardly facing step surface or abutment 50. As will now be apparent, the rings 28 and 30 cooperate with the opposite ends of the segmental back-up ring 26. Each of the rings 28 and 30 are provided with a center aperture 52 so that they may slide on the rod-like element 16.

When the packing structure 14 is assembled on the rod-like element 16, as shown in FIGURE 2, the lower ring 30 abuts the abutment portion 24 of rod-like element 16 and thus is prevented from moving longitudinally outwardly of the rod-like element 16, whereas the upper ring 28 abuts the end of packer 18 opposite the end which abuts the piston 20. Referring now to FIGURE 3, it will

be noted that when the segments 32 of ring 26 are in a retracted position, the surface 44 is spaced from the surface 50 of ring 28. As ring 28 moves toward ring 30, when the piston 20 is extended, the inclined surfaces 45 and 48 of the rings 28 and 30 cooperate with the inclined surfaces 40 and 42 of the segments to cause the segments to wedge apart and move radially with respect to the longitudinal axis of the segmental ring 26. The segments 32 will continue to move outwardly until the outwardly facing surfaces 44 engage the inwardly facing surfaces 50 of the rings 28 and 30 respectively. This limits further outward movement of the metallic segments 32 just short of the plastic lining C on the wall of the pipe 12 and thus protects the lining from being crushed. While the segmental ring 26 does not engage the wall of the well pipe 12, there is such a small clearance between the segments and the wall that the back-up ring effectively blocks any tendency of the packer 18 to flow when the packer is subjected to subsequent extreme pressures.

Referring now to FIGURE 5, a slightly modified form of back-up ring structure 22' is disclosed. In this embodiment of the invention, the arcuate segments 32' of the segmental ring 26' are provided with inwardly tapered ends 48' so that when they are assembled as a unit, the surfaces 40' defined by the ends of the segments are an inverted cone. The rings 28' and 30' are provided with a complementary cone surface 46', and it will be understood that when the ring 28' is moved toward the ring 30' the surfaces 46' wedge against the surfaces 40' and cause the segments 32' to move radially outwardly.

In order to provide a stop for the metallic segments 32' so that they will not engage the lining of the well pipe 12, the elastomeric retaining band 38' has a greater radial thickness than the depth defined by the grooves 36' in the peripheral surfaces of the arcuate segments 32'. By such an arrangement, the outer peripheral surface of the resilient retaining band 38' is spaced outwardly from the outer peripheral surface 34' of the segments 32'. When the rings 28' and 30' are moved relatively toward one another, the segments 32' of the segmental ring 26' expand radially until such time that the outer surface of the retaining band 38' engages the plastic lining C of pipe 12. Since the band 38' is as soft or softer than the lining of the well pipe 12, there is no damage to the lining upon contact by the band 38'. In effect, the band 38' engages the well pipe wall and provides a stop to prevent the segments from moving radially outwardly into engagement with the well pipe.

By utilizing an endless retainer band made of an elastomeric material such as rubber, synthetic rubber or the like, in both of the environments of the present invention shown, a greater radial expansion of the segmental back-up ring can be obtained. In the past, coil springs and snap rings have been utilized to retain arcuate segments of a segmental back-up ring in position, but such prior springs or snap rings do not have sufficient elasticity or ability to maintain the segments in a relative position to one another as they are being expanded.

While the invention has been primarily disclosed in relation to its preferred use with a packing structure of a tester tool for oil and gas well flow tubing, it is, of course, within the scope of the present invention that the improved packing structure could be used in flow tubing or casing wherever it is desired to form a seal between any rod-like element of a well tool and the wall of the tubing or casing. Therefore, the terminology used in this specification is for the purpose of description and not for limitation as the scope of the invention is defined in the claims.

What is claimed is:

1. In a packing structure for forming a seal between a rod-like element and a surrounding wall of a well pipe or the like: a substantially cylindrically-shaped resilient packer mounted on the rod-like element; a pair of annular ring elements carried on said rod-like element and each

having a cone shaped surface on one end thereof, one of said ring elements abutting an end of said packer; an expandible segmental back-up ring carried on the rod-like element and having inverted cone shaped surfaces on each end thereof, said segmental back-up ring being interposed between said pair of annular ring elements with the cone surface of each annular ring element abutting respectively the inverted cone surfaces of said segmental back-up ring, said segmental back-up ring including a plurality of metallic segments; resilient means circumscribing said segmental back-up ring for maintaining the segments in a retracted position as a unit; means abutting the other of said ring elements and maintaining the same stationary with respect to said one ring element; means engaging said packer on the end opposite to the end engaging said one ring element for compressing said packer longitudinally and expanding the same transversely while also causing said annular ring elements to move toward one another to radially expand said segmental back-up ring; and means on each of said annular ring elements and on each end of said expandible segmental back-up ring for limiting radial expansion of the same to a predetermined amount.

2. In a packing structure for forming a seal between a rod-like element and a surrounding wall of a well pipe or the like: a substantially cylindrically-shaped resilient packer mounted on the rod-like element; a pair of annular ring elements carried on said rod-like element and each having a cone shaped surface on one end thereof, one of said ring elements abutting an end of said packer; an expandible segmental back-up ring carried on the rod-like element and having inverted cone shaped surfaces on each end thereof, said segmental back-up ring being interposed between said pair of annular ring elements with the cone surface of each annular ring element abutting respectively the inverted cone surface of said segmental back-up ring, said segmental back-up ring including a plurality of metallic segments; resilient means circumscribing said segmental back-up ring for maintaining the segments in a retracted position as a unit; means abutting the other of said ring elements and maintaining the same stationary with respect to said one ring element; means engaging said packer on the end opposite to the end engaging said one ring element for compressing said packer longitudinally and expanding the same transversely while also causing said annular ring elements to move toward one another and to radially expand said segmental ring and means on said annular ring elements and said expandible back-up ring for limiting radial expansion of the same to a predetermined amount, said last-mentioned means including an annular ridge on each of said ring elements, each ridge defining an inwardly facing surface, and said expandible segmental back-up ring having an annular

ridge on each of its ends defined by projections on the ends of its segments, the annular ridges on the ends of said segmental back-up ring having outwardly facing surfaces spaced from the inwardly facing surfaces of the respective ridges of said annular rings when said back-up ring is in the retracted position.

3. In a packing structure for forming a seal between a rod-like element and a surrounding wall of a well pipe or the like: a substantially cylindrically-shaped resilient packer mounted on the rod-like element; a pair of annular ring elements carried on said rod-like element, one of said ring elements abutting an end of said packer, each of said ring elements having opposed surfaces which are double cone shaped and define an inwardly facing step surface; an expandible segmental back-up ring carried on the rod-like element and interposed between said pair of annular ring elements, said segmental back-up ring including a plurality of metallic segments, said segmental back-up ring having opposite ends which are each inverted double cone shaped defining an outwardly facing step surface for cooperating respectively with respective inwardly facing step surfaces of said annular ring elements; resilient means circumscribing said segmental back-up ring for maintaining the segments in a retracted position as a unit with the step surfaces in the ends thereof spaced from the step surfaces of the respective annular rings; means abutting the other of said annular ring elements and maintaining the same stationary with respect to said one ring element; and means engaging said packer on the end opposite to the end engaging said one ring element for compressing said packer longitudinally and expanding the same transversely while also causing said annular ring elements to move toward one another to radially expand said segmental back-up ring until the outwardly facing step surfaces on the ends of the said back-up ring abut the respective inwardly facing step surfaces on the annular rings.
